UNITED STATES PATENT OFFICE.

RODOLPHE CHRISTESEN, OF NEW BRITAIN, CONNECTICUT, ASSIGNOR TO THE
RUSSELL & ERWIN MANUFACTURING COMPANY, OF SAME PLACE.

DESIGN FOR A HINGE.

SPECIFICATION forming part of Design No. 16,906, dated September 21, 1886.

Application filed January 9, 1886. Serial No. 188,118. Term of patent 14 years.

To all whom it may concern:

Be it known that I, RODOLPHE CHRISTESEN, a citizen of the United States, residing at New Britain, in the county of Hartford and State of Connecticut, have invented and produced a new and original Design for the Ornamentation of a Hinge, of which the following is a specification, reference being had to the accompanying drawing, forming part thereof, in which the only figure is a front elevation.

Heretofore hinges have been made with a raised border around the edge of each leaf on its face side, and with various ornaments in relief on the space inclosed by said border. The leading feature of my design consists of the ornamental work on the face of the hinge-leaves, which extends from the inner edge of each leaf in the form of the leaves of an old-fashioned ornamental strap-hinge. I form this design in relief on what is generally called a paneled hinge. On that portion of the panel-border which is nearest the hinge hub or knuckles I form on each leaf, at the middle of its length, a side extension having right-angled corners *aa* and a semicircular middle portion, *b*. From the middle of this semicircular middle portion the main ornament continues laterally to near the opposite edge of the leaf, and then divides into scrolls *cc*, which

roll backward toward the inner edge of the leaf. I form the screw-holes *dd* in a branch of the scrolls *cc*. The ground or sunken surface of the panel is ornamented by transverse corrugations or beads; but this may be changed without changing the character of the ornamentation in relief before described, the main portion of which ornament, taking both leaves together, is the representation of an old-fashioned ornamental strap-hinge.

I claim—
The design for the ornamentation of a hinge-leaf herein shown and described, which consists of the side extension having right-angled corners *aa*, and the semicircular middle portion, *b*, extending from that portion of the panel-border which is nearest the hinge hub, and the main arm or bar extending from said side extension toward the opposite edge of the leaf, where it divides into scrolls *cc*, which roll backward toward the inner edge of the leaf, the same constituting a representation of the leaf of an old-fashioned ornamental strap-hinge.

RODOLPHE CHRISTESEN.
